EXTENSION HANDLE FOR CEMENT
FINISHING TOOLS

James E. Gibson, 3945 W. Ave. 43, Los Angeles 41,
Calif., and Samuel N. Summers, La Crescenta, Calif.;
said Summers assignor to said Gibson

Filed Sept. 6, 1963, Ser. No. 307,052
2 Claims. (Cl. 306—19)

This invention relates to concrete surface finishing tools and more particularly to an extension handle means therefor.

The principal objects of the invention are: to provide an extension handle means that can be quickly attached to and detached from the normal hand held tools for finishing cement surfaces such as floors, walks and the like; to provide a tool handle engaging means of the above character which is capable of engagement with the tool handles regardless of whether the tool handles are supported at one end or both ends; to provide an extension handle of the above character which permits movement of the extension handle relative to the tool held thereby around axes which are at right angles to each other together with means for affording variable frictional resistance to such movements; and to provide an extension handle means for cement finishing tools in which all of the foregoing objectives are realized in practice and which is simple and sturdy in construction and effective for its intended purpose.

With the above objects in view, together with such additional objects and advantages as may subsequently appear, the invention resides in the parts, and in the construction, combination and arrangement of parts described, by way of example, of the following specification of a presently preferred embodiment of the invention, reference being had to the accompanying drawing which form a part of said specification and in which drawings:

FIG. 1 is a side elevational view of the said presently preferred embodiment of the invention attached to a cement edge finishing tool of the type having the handle thereof supported at both ends,

FIG. 2 is a top plan view of the embodiment shown in FIG. 1,

FIG. 3 is a side elevational view similar to FIG. 1 with the finishing tool eliminated,

FIG. 4 is a top plan view of the device as shown in FIG. 3 and with the tool handle gripping jaws open for engagement with the finishing tool handle means,

FIG. 5 is a rear elevational view partly in section taken on the line 5—5 of FIG. 1,

FIG. 6 is a transverse sectional view taken on the line 6—6 of FIG. 1 showing details of the means by which the device is clamped to a tool handle,

FIG. 7 is a side elevational view of the device showing the attachment thereof applied to the cement surface finishing tool known as a float said tool being of the type having the handle thereof supported at its forward end only, and

FIG. 8 is a rear elevational view of the invention as shown in FIG. 7.

Referring first to FIGS. 1 through 6 of the drawings, the illustrated embodiment of the invention comprises a rigid long handle 1 which may be of wood as shown or which may also be of light tubular metal. At its forward end, the handle 1 carries a metal ferrule 2 in which the arms of a yoke 3 are secured by suitable means such as the rivet 4. The yoke arms straddle one end of a block 5 and are pivotally secured thereto by a bolt 6 passing therethrough and carrying a wing nut 7 by which the yoke arms may be caused to clamp the block 5 with a desired degree of tightness.

2

The block 5 is provided with a bore 8 extending therethrough and in which bore the threaded portion 9 of a locking bolt 10 extends with the threaded end of the bolt projecting beyond the side of the block 5 and carrying a washer 11 and a wing nut 12 to which further reference will be made. Loosely mounted on the body of the bolt 10 and spaced slightly inwardly of the block 5 is a first tool handle engaging jaw 13 restrained against movement axially of the bolt by engagement with nuts 14 and 15 at each side of the jaw while allowing the jaw 13 freedom to turn on the bolt. Also loosely mounted on the bolt 10 adjacent to the head end thereof is a second tool handle engaging jaw 16 which is a mirror image duplicate of the jaw 13. Each of the jaws 13 and 16 is formed of a strip of resilient metal and is provided with a hole 17 adjacent to one end 18 thereof through which the body of the bolt 10 extends, said ends adjacent to said hole being bent at right angles toward each other to form tool rib engaging members 19. The jaws 13 and 16 are sufficiently long so that the opposite ends 20, 20 thereof can engage one support S of the handle H of a tool T while the ends 18, 18 thereof are engaging the other handle support S' as best shown in FIGS. 1 and 2. Preferably, the support engaging faces of the ends 20, 20 of the jaws are serrated as at 21. Between the engagement of the jaws 13 and 16 with the bolt 10 and the ends 20, 20 thereof, the jaws are curved outwardly from each other as at 22, 22 for a purpose to be later referred to.

Also mounted on and surrounding the bolt 10 and extending between the opposed faces of the jaw 13 and the block 5 is a heavy compression spring 23 of sufficient diameter to surround the nut 14; said spring normally tending to move the block 5 away from the jaw 13 and providing frictional resistance to movement of the handle 1 about the bolt 10 by a force derived from adjustment of the wing nut 12. The head end of the bolt 10 beyond the outer face of the jaw 16 carries a cross pin 24 on which is pivoted a cam lever 25 formed of a piece of sheet metal doubled on itself and straddling the bolt head, said lever having a camming face 26 of gradually increasing radial dimension as it is moved to tool clamping position and a handle 27 by which it may be swung on the cross pin 24. Having reference to FIGS. 2 and 4, FIG. 4 shows the device open ready for installation on the finishing tool handle. The finishing tool is inserted first between one end of the jaws and then the other so that the handle supports S and S' are received between the jaws and then the lever 25 is swung in a clockwise direction as viewed in these figures causing the jaws 13 and 16 to grip the handle supports and by the resilience of the portions of the jaws between the supports S and S' to clamp the tool tightly between the jaws; it being understood that prior to such time, the jaw 13 will have been adjusted by the nuts 14 and 15 into such proximity with relation to the jaw 16 and the cam lever 25 that secure locking of the device on the tool will be achieved. The tool can then be employed to finish the concrete surface with the user in a standing position and also permits portions of the concrete surface to be finished which could not be otherwise reached. As soon as the work with one tool is completed it can be detached from the handle means and the next tool to be employed quickly attached.

Referring finally to FIGS. 7 and 8, there is shown the use of the device as an extension handle for a float F having a handle H' supported at its forward end only by support S'' and having a central longitudinal stiffening rib R on the upper surface of the blade B. For such tools, the jaws 13 and 16 are swung on the bolt 10 to a vertical position with the jaw ends 19, 19 engaging opposite sides of the rib R and with the handle H' re-

ceived in the opposed curved portions 22, 22 of the jaws, the bolt 10 being thus positioned between the points of engagement with the rib R and handle H'. Operation of the lever 25 causes the jaws 13 and 16 to resiliently grip the rib R and handle H thus making the float available for long handle use. It is to be noted that the device is thus adapted for immediate attachment to the two general types of handles on hand finishing tools for cement surfaces without any change.

By means of this invention, the user does not need to carry one set of tools for hand use and another set of tools with long handles and since the device is quickly attached and detached, only one long handle need be added to his set of tools. The friction of the engagement of the yoke 3 with the block 5 and the block 5 with the tool for movement about the axis of the bolt 10 can be adjusted by the respective wing nuts to suit the preference of the individual user, the friction being such that the tools can be lifted from the surface in a manner which does not disturb the smoothness of the soft cement.

Thus there has been created an extension handle for cement finishing tools which is adapted to the different types of handle structure for such tools and which gives the ordinary hand held tools the capacity for long handle use.

While the foregoing specification and drawings have disclosed a presently preferred embodiment of the invention by way of example, the invention is not to be deemed to be limited to the precise details thus disclosed, and it will be understood that the invention includes, as well, all such changes and modifications in the parts, and in the construction, combination and arrangement of parts as shall come within the purview of the appended claims.

We claim:

1. An extension handle having a ferrule rigidly attached at one end thereof and a yoke immovably mounted to said ferrule and having opposed holes in the free end, a quick detachable clamping means secured to said yoke comprising a block having two passage through it, said passages being directed transversely to each other and

at opposite ends of said block, said block being positioned between the arms of said yoke, a bolt passing through the opposed holes in said yoke and through one of said passages in said block to adjustably secure said block in said yoke, an elongated second bolt passing through said other block passage and being adjustably secured thereto, tool gripping means including duplicate shaped jaws, a hole in each jaw of said clamp means, said second bolt being disposed through said holes, means immovably securing one of said jaws to said bolt, resilient means urging said jaw away from said rigidly mounted block and a cam lever attached to one end of said second bolt whereby said jaws may be moved to closed position to grip a tool.

2. An extension handle as claimed in claim 1 in which said second bolt has nut means threaded thereon and located against said block on the side remote from said jaws whereby said nut means may be turned to vary the position of said bolt relative to said block.
